United States Patent [19]

Dennis

[11] Des. 270,943

[45]  Oct. 11, 1983

[54] COVER PLATE FOR CEILING FANS

[75] Inventor: Warren E. Dennis, Pasadena, Calif.

[73] Assignee: Casablanca Fan Company, Inc., City of Industry, Calif.

[] Term: 14 Years

[21] Appl. No.: 332,744

[22] Filed: Dec. 21, 1981

[51] Int. Cl. .... D23—04

[52] U.S. Cl. D23/163

[58] Field of Search .... D23/151—166;
D26/51, 59, 72; 416/5, 204, 206, 210 R, 241,
248

[56] References Cited

U.S. PATENT DOCUMENTS

D. 256,614 8/1980 Hoyt D23/163

D. 262,570 1/1982 Lock D23/158

D. 263,499 3/1982 Markowitz D23/163

D. 267,195 12/1982 Gomes D23/163

D. 267,196 12/1982 Gomes D23/163

OTHER PUBLICATIONS

Home Lighting & Accessories, Apr. 1980, p. 29, center left item.

Moss Manufacturing, Inc., "The Heirloom Collection" Brochure, dated Jun. 12, 1980, front cover.
Perievlauaz "The Ceiling Fan Specialists" Brochure, dated Jun. 12, 1980, front cover.

Primary Examiner—James R. Largen
Attorney, Agent, or Firm—Charles H. Schwartz;
Ellsworth R. Roston

[57] CLAIM

The ornamental design for a cover plate for ceiling fans, substantially as shown.

DESCRIPTION

FIG. 1 is a top perspective view of a cover plate for ceiling fans showing my new design;

FIG. 2 is a side elevational view thereof; and

FIG. 3 is a bottom plan view thereof.

FIG. 1

FIG. 2

FIG. 3